(57) **CLAIM**

The ornamental design for a golf putter for custom fitting, as shown and described.

DESCRIPTION

FIG. 1 is a front elevational view of a golf putter for custom fitting showing my new design in a centered position; FIG. 2 is a rear elevational view of the golf putter for custom fitting;

FIG. 3 is a side elevational view of the golf putter for custom fitting, the opposite side being a mirror image thereof; FIG. 4 is a rear elevational view of the golf putter for custom fitting; the shaft portion being shown in an alternate position; and,

FIG. 5 is a rear elevational view of the golf putter for custom fitting; the shaft portion being shown in an alternate position. The top end of the putter handle and the bottom surface of the putter are plain and unornamented.

The broken away section of the handle is shown due to indeterminate length.
